6 Claims

ABSTRACT OF THE DISCLOSURE

The safety lock apparatus includes a pivotal hook portion for underlying in a normally non-supporting relationship a basketball backstop frame that has been raised to a storage position by a winch. The hook portion will catch and support the backstop frame if the winch should fail. A solenoid connected to the hook portion and to the winch moves the hook portion from its underlying position when the backstop is about to be lowered.

BACKGROUND OF THE INVENTION

This invention relates to a safety device and, more particularly, to a safety lock apparatus for use with basketball backstops.

Generally, gymnasiums, field houses and the like, are used for a variety of activities in addition to basketball games. Thus the basketball backstops, which are supported by rafters or some other portion of the ceiling structure, are provided with means enabling them to be moved from a playing position to a storage position when basketball is not being played. The backstops are generally carried by pivotally mounted frameworks swingable forwardly or rearwardly from playing position to a generally horizontal storage position near the ceiling. It is also known to use backstops wherein the framework moves vertically from its playing position to a raised storage position.

Usually these backstop frames are raised and lowered by electrically operated winches. When stored, a backstop frame such as described, is held only by a cable extending from the winch. If, for any reason, the cable or the winch should fail while the backstop is stored, the latter would fall suddenly to its playing position. This sudden fall could cause extensive damage to the backstop frame and the supporting structure on the ceiling.

SUMMARY OF THE INVENTION

Briefly, the invention relates to a basketball backstop safety apparatus including a support means and a backstop frame connected to the support means for movement between playing and storage positions. Drive means such as a winch is connected to the backstop frame and is operable to move the backstop frame between the playing and storage positions. Safety lock means is connected to the support means and includes a lock member movable between a locked position underlying the backstop frame when the backstop frame is in said storage position to retain the frame in the storage position in the event of failure of the drive means and an unlocked position to permit movement of the backstop frame from the storage position to the playing position.

BRIEF DESCRIPTION OF THE DRAWINGS

FIG. 1a is a side elevational view showing the arrangement of the safety lock, the winch and the backstop frame when the backstop is in its playing position in accordance with the invention;

FIG. 1b is a view similar to FIG. 1a showing the backstop frame locked in its storage position;

2

FIG. 2 is a detailed perspective view of the safety lock in accordance with the invention;

FIGS. 3a, 3b and 3c are detailed side elevational views showing in sequence the relationship of the backstop frame to the safety lock device as the backstop frame is raised to its storage position and descends therefrom toward its playing position; and

FIG. 4 is a schematic representation of an electrical circuit for operating the apparatus of FIG. 1.

10 DESCRIPTION OF A PREFERRED EMBODIMENT

In FIGS. 1a and 1b, a portion of a field house or gymnasium ceiling 10 is shown. In a preferred form of the invention, backstop frame 12, including backboard 14 and basketball goal 16, is supported from the ceiling 10 by pivots 18 so that it can be pivoted into a storage position as shown in FIG. 1b. The safety lock 20 is supported by the ceiling and is preferably positioned in spaced relation to the pivots 18 so that it is in the path of a portion of the backstop frame, such as the spreader pipe 22, when the frame moves to its storage position. When used with a vertically movable backstop frame, the safety lock must be able to engage a portion of the frame when it is stored in its raised position.

15 The backstop frame is raised and lowered by cable or rope 24 which is reeled on winch 26. The winch is powered by electric motor 28. Winch 26 and safety lock 20 are electrically interconnected for coordinated movement when the backstop frame is lowered in a manner fully disclosed hereinafter.

20 Referring to FIG. 2, the safety lock 20 includes a housing 30 which is connected to the ceiling 10 by support 32. Depending hook means 36 is connected to the housing 30 by pivot 34.

25 The hook means 36 comprises a shank 38 whose upper portion is welded or otherwise affixed to a sleeve 40 which in turn is mounted for rotation about the pivot 34. The pivot 34 may include a fixed pin about which the sleeve 40 is rotatable. A flange 42 on angle member 43 is disposed in transverse relation to shank 38 intermediate the ends thereof. Cam flat 44, a flat elongated member disposed in fixed angular relation to shank 38, has one end 46 welded to the lower end of shank 38 and has an intermediate portion welded to the free edge 48 of transverse flange 42 whereby an upward force urges the cam flat 44 and the hook means 38 counterclockwise about pivot 34. The end of cam flat 44 extending beyond free edge 48 is bent to an angle intermediate that of cam flat 44 and shank 38 to form catch 49. This arrangement of elements results in a hook defined by shank 38, flange 42 and catch 49 which hook functions as a lock member as hereinafter described.

30 Solenoid 52 is operable to pivot hook 36 from a locked position shown in FIG. 3b to an unlocked position shown in FIG. 3c. The solenoid 52 includes an armature 54 axially movable in the solenoid coil and pivotally connected to link 56. Link 56 is connected to the upper portion of shank 38 by outwardly extending arm 58. The housing 30 is provided with a stop 62 to limit clockwise movement of the hook means 36.

35 A guide flat 50, adapted to be cammed by the backstop frame, depends from a sleeve 67 which is rotatable about a pivot 68 connected to housing 30. The guide flat 50 is adjacent to hook means 36. The upper portion 51 of guide flat 50 depends below the juncture of the flange 42 and cam flat 44. The lower end of guide flat 50 is bent to form a cam surface 53 that slopes outwardly away from hook means 36.

40 Thus cam flat 44 and guide flat 50 define a converging passage 74 to enable them to be engaged by the spreader pipe 22 as the backstop frame is moved to its storage position. Upon such engagement, the spreader pipe 22

urges hook 36 counterclockwise and guide flat 50 clockwise about their respective pivots.

A normally open switch 80, including operator 82, is mounted on housing 30 adjacent the guide flat 50 so that the clockwise movement of the guide flat causes operator 82 to close the switch. Switch 80 is electrically connected to the solenoid 52 for operation thereof in a manner to be explained.

A normally closed switch 86 (FIG. 2) is connected to the underside of the housing 30 between the hook pivot 34 and guide flat pivot 68. The operator 90 for normally close switch 86 depends below the housing as illustrated in FIG. 3 to be engageable by the upwardly moving spreader pipe 22. Switch 86 is electrically connected to motor 28 which drives the winch 26 in a manner which will be explained in detail.

Referring to FIG. 4 wherein a schematic diagram of the circuit for the safety lock apparatus is illustrated, a power source 100 is connected by a wire 102 to a manually operable three-way switch 104 operatively connected to the winch motor 28 for raising and lowering the backstop frame. Switch 104 includes an "up" pole 106, a "down" pole 108 and an "off" position 110. The "up" pole 106 is connected by line 112 to normally closed switch 86. Line 114 connects the normally closed switch 86 to the motor 28 for winch 26.

The "down" pole 108 is connected by line 120 and line 122 to normally open switch 80. Line 124 connects normally open switch 80 to the solenoid 52. Line 126 connects "down" pole 108 through line 120 to a downward rotary counting limit switch 128 which is in turn connected by line 130 to the motor for winch 26. Ground wires 132, 134, and 136 connect the winch motor and solenoid to the source 100.

The operation of the safety lock can best be described by reference to FIGS. 2, 3, and 4. In FIG. 2, the safety lock is shown fixed to a ceiling in its normally closed or locked position. Normally closed switch 86 (FIG. 2) is closed so that the circuit to the winch motor 28 may be completed while the circuit to the solenoid 52 is open. When three-way switch 104 is actuated to raise the backstop, a circuit is completed through "up" pole 106, line 112, normally closed switch 86 and line 114 to drive the winch motor 28. As the spreader pipe 22 on the backstop 12 moves upwardly (FIG. 3a), it enters the converging passage 74 defined by cam flat 44 and guide flat 50. As it continues upward, it engages the cam flat 44 urging the hook counterclockwise out of its path. At the same time, the spreader pipe upon engagement with cam surface 53 urges guide flat 50 clockwise about its pivot. The clockwise movement of the guide flat 50 causes operator 82 to close normally open switch 80 enabling the circuit through the solenoid 52 to be completed. When the spreader pipe has moved past catch 49 on cam flat 44, hook means 36, under its own weight, returns to its normal position where it serves as a safety lock by underlying the spreader pipe 22 (FIG. 3b).

The winch 26 continues to raise the backstop until the spreader pipe 22 contacts operator 90 for the normally closed switch 86 to open the circuit to the winch motor 28. When the winch is shut off, the backstop frame and spreader pipe are disposed as shown in FIGS. 1b and 3b.

To lower the backstop from the storage position, switch 104 is moved to its "down" position. This completes a circuit through pole 108, line 120, line 122 and normally open switch 80 (now closed) and line 124 to the solenoid 52. The energization of the solenoid 52 causes the hook 36 to pivot into position shown in FIG. 3c, where it is displaced from under the spreader pipe 22, thus releasing it for downward movement. Another circuit from pole 108 through line 120, line 126, downward rotary counting limit switch 128 and line 130 actuates winch motor 28 to lower the backstop. As the backstop is lowered and the spreader pipe moves away from operator 90, switch 86 returns to its normally closed posi-

tion. As the downwardly moving spreader pipe disengages guide flat 50, it returns to its normal vertical position, thus causing operator 82 to open switch 80. This de-activates the solenoid 52 and permits the hook 36 to return to the position shown in FIG. 3a by its own weight. The backstop continues downward until it reaches the playing position (FIG. 1a) where the downward rotary counting limit switch 128 opens to break the circuit to the winch.

While the hook underlies the spreader pipe 22 in the safety locked position (FIG. 3b), if the winch or cable should fail, the fall of the backstop would be checked by flange 42. Since it cannot slip off the hook, the backstop will be held in its storage position until the winch or cable is repaired.

If the circuit is energized to lower the backstop while the spreader pipe is resting on the hook, the solenoid will not respond since the weight of the backstop will prevent the catch 49 from sliding past the spreader pipe. Because of this, there is no danger of inadvertently removing the hook while it is supporting the backstop. In addition, a warning that the winch or cable has failed is given when the apparatus does not lower the backstop when the "down" circuit is energized.

While the safety lock apparatus of the above-disclosed invention has been described with reference to a particular embodiment, it is to be understood that various modifications can be made without departing from the scope of the invention which is defined only by the appended claims.

What is claimed is:

1. A basketball backstop safety apparatus which comprises
  - support means;
  - a backstop frame connected to said support means for movement between playing and storage positions;
  - drive means connected to said backstop frame and operable to move said frame between said playing and storage position; and
  - safety lock means connected to said support means including a lock member movable between a locked position and an unlocked position, said locked position being in underlying and non-supporting relation to said backstop frame when said backstop frame is in said storage position to thereby retain said frame in said storage position in the event of failure of said drive means, said unlocked position being in non-underlying relation to said backstop frame to permit movement of said backstop frame from said storage position to said playing position.
2. A safety apparatus as defined in claim 1 wherein said lock member includes hook means normally disposed in said locked position and pivotally movable to said unlocked position; and said safety lock means includes:
  - power means connected to said hook means and operable to move said hook means to said unlocked position; and
  - control means interconnecting said drive means and said power means to cause said hook means to move to said unlocked position when said drive means is operated to lower said backstop.
3. A safety apparatus as defined in claim 2 wherein said control means includes an electrical circuit for operating said power means;
  - said electrical circuit including normally open switch means mounted on said safety lock means in a position to be closed by said backstop frame when said backstop frame is in said storage position.
4. A safety apparatus as defined in claim 3 wherein said control means is connected to said drive means so that energization of said drive means to move said backstop from said storage position to said playing position completes said electrical circuit to move said hook means to said unlocked position.

5. A safety apparatus as defined in claim 1 wherein said lock member includes hook means having a shank pivotally connected to said housing and having first cam means supported by said shank; said cam means being operable when engaged by said backstop frame to urge said hook means from said locked position to permit said backstop frame to move to said storage position; and

said safety lock means includes power means connected to said hook means and operable when energized to move said hook means to said unlocked position. 10

6. A safety apparatus as defined in claim 5 further comprising:

an electrical circuit for operating said power means, 15 said circuit including normally open switch means; a second cam means pivotally connected adjacent said first cam means and positioned for engagement by said backstop frame as it moves toward said storage

mounted adjacent said second cam means to be closed when said second cam means is engaged by said backstop; and
5 said first and second cam means defining a converging path therebetween and adapted to be oppositely pivoted when they are engaged by said backstop frame as it moves to said storage position.
